Primary Examiner—Louis S. Zarfas**Assistant Examiner**—Eric Watterson**Attorney, Agent, or Firm**—Myron B. Kapustij; Leon E. Redman[57] **CLAIM**

The ornamental design for a faucet, as shown and described.

DESCRIPTION

FIG. 1 is a front perspective view of a faucet showing my new design;

FIG. 2 is a rear perspective view thereof;

FIG. 3 is a top plan view thereof;

FIG. 4 is a front elevational view thereof;

FIG. 5 is a right side elevational view thereof, the left side being a mirror image;

FIG. 6 is a rear elevational view thereof; and,

FIG. 7 is a bottom plan view thereof.

The broken line showings of the aerator in FIGS. 1-2, 4-5 and 7, of the handles in FIGS. 1-7, and of the escutcheon in FIGS. 1-7 are for purposes of illustration only and form no part of the claimed design.
